UNITED STATES PATENT OFFICE.

RAYMOND W. DULL, OF CHICAGO, ILLINOIS.

SEPARATOR.

1,155,473.

Specification of Letters Patent.

Patented Oct. 5, 1915.

Application filed April 20, 1914. Serial No. 833,047.

To all whom it may concern:

Be it known that I, RAYMOND W. DULL, a citizen of the United States of America, and resident of Chicago, Cook county, Illinois, have invented a certain new and useful Improvement in Separators, of which the following is a specification.

My invention relates to separators of the kind employed in separating water from sand, and more particularly to sand separators of this character in which a receptacle receives the sand and water, and in which means are provided for discharging the water from the top of the receptacle and the sand from the lower end thereof, the automatic discharge of sand being controlled by a valve which is operated by the downward movement of the receptacle under the weight of the contents thereof.

Generally stated, the object of my invention is to provide a novel and highly efficient sand separator of the foregoing general character.

A special object is to provide a novel construction and arrangement whereby the receptacle moves bodily downward, instead of tilting about an axis, and whereby a sand valve at the lower end of the receptacle is automatically opened and closed by this bodily up and down movement thereof.

It is also an object to provide certain details of construction and combinations tending to increase the general efficiency of a sand separator of this particular character and tending to render the same more satisfactory and certain in its operation than heretofore.

To the foregoing and other useful ends my invention consists in matters hereinafter set forth and claimed.

In the accompanying drawings, Figure 1 is a side elevation of a sand separator embodying the principles of my invention. Fig. 2 is a horizontal section, on a smaller scale, on line 2—2 in Fig. 1. Fig. 3 is a vertical section, on a smaller scale, on line 3—3 in Fig. 1. Fig. 4 is a perspective, also on a smaller scale, of the baffle plate which is employed for preventing the sand from overflowing with water.

As thus illustrated, and referring more particularly to Fig. 1, my invention comprises a receptacle which is shaped like an inverted cone, being provided with hangers α at the upper end thereof, and with a discharge opening α^1 at the lower end thereof.

Said hangers have knife edges α^2 which rest on the upper edges of the plates α^3 , the latter having seats or notches α^4 for this purpose. These plates α^3 are also provided with openings α^5 for the U-bolts α^6 which extend vertically through the beams B or other structural members of the frame upon which the separator is supported. This frame, it will be seen, affords access to the top of the receptacle. A lever C is secured to the plate α^3 at the right in Fig. 1, and a lever D is secured to the plate α^3 at the left in the figure. The two levers are of different lengths, as shown, and the end of the lever D is connected with the middle of the lever C by a link E of any suitable character. Thus a supporting mechanism is provided for sustaining the weight of the separator receptacle. Disposed a distance above these levers is a counterbalance arm or lever F which is pivoted at f upon a bracket f^1 secured to the stationary frame of the separator, or which is joined to the supporting mechanism in any suitable manner. A link f^2 is provided for connecting the end of the lever C with the short end of the lever F, the longer end of the latter being provided with a counterweight f^3 which is adjustable thereon for the purpose of regulating the operation of the separator. In other words, and by means of this counterbalancing weight, the receptacle can be caused to move downward with either a full load or any fraction thereof.

The automatic valve G controls the opening α^1 and is fixed to the lower end of a rod g that slides up and down in a tube or housing g^1 disposed centrally of the receptacle, the upper end of said tube being firmly held in place by a clamp g^2 , or by any other suitable means. The lower end of said tube or guide g^1 can be held in place in any suitable manner, it being understood that this tube is preferably large enough to give the said rod some lateral play therein. The upper end of said rod is connected with the lower end of the link E, it being understood that the three pivotal connections of this link are loose or of any other character which will permit the two levers C and D and the rod g to move up and down in the desired manner and without causing any binding or cramping of the parts. With this construction and arrangement, the valve G moves downward faster than the receptacle, with the result that the discharge opening α^1 is

automatically opened by the bodily downward movement of the receptacle. The valve G is provided with means to engage the valve seat at the lower end of the receptacle, thus forming means on said rod to limit the motion thereof and thereby determine the extent of movement of the receptacle. A nut g^3 on the rod may serve as an adjustable stop to limit the downward movement, as the valve will not open farther after the nut g^3 engages the top of the clamp g^2 , thus determining the extent to which the valve will open when the receptacle moves downward. However, the downward movement can be limited by any suitable means. After the sand has been discharged in this manner, the receptacle then automatically moves upward.

A horizontally disposed baffle plate H is provided near the top of the receptacle, within the same, and at one side of the center thereof, said plate having a vertically disposed flange h^1 which is secured to the clamp g^2 at the center of the structure, and which has its outer ends secured to the receptacle by brackets h^1 , or by any other suitable means. In this way the upper end of the tube g^1 is held in position by the baffle plate. The edge portion h^2 of this baffle plate is disposed a distance from the sides of the receptacle, thereby forming a space h^3 , and is secured by brackets h^4 to the side walls of the receptacle. The water and sand are discharged on to the plate H toward the flange h thereof, the water overflowing the said flange and escaping from the other side of the receptacle where it is discharged therefrom through a spout L, or by any other suitable means. On the other hand, the sand washes backward away from the flange h , with a certain percentage of the water, and is discharged through the space h^3 to the receptacle. In this way the sand is all precipitated into the receptacle, and practically nothing but water and the mud held in suspension thereby are discharged from the spout at the other side of the receptacle.

I do not limit myself to the exact construction shown and described.

What I claim as my invention is:—

1. A sand separator comprising a receptacle having a discharge opening, supporting mechanism for said receptacle, arranged above the same, whereby said receptacle is movable up and down bodily, counterbalancing means for normally holding the receptacle in raised position, adjusted to permit the receptacle to move downward under a load, and a valve for said opening, connected above with said mechanism to open when the receptacle moves downward, said mechanism including a lever having a fixed axis, a link connecting said lever with said means, and a hanger se-

cured to said receptacle, engaging said lever at a point between said axis and link.

2. A sand separator comprising a receptacle having a discharge opening, supporting mechanism for said receptacle, arranged above the same, whereby said receptacle is movable up and down, counterbalancing means for normally holding the receptacle in raised position, adjusted to permit the receptacle to move downward under a load, and a valve for said opening, connected with said mechanism to open downwardly when the receptacle moves downward, said mechanism comprising a pair of levers having fixed axes, connected together where said mechanism is connected with said valve, and connections from one lever to said counterbalancing means.

3. A sand separator comprising a receptacle having a discharge opening, supporting mechanism whereby said receptacle is movable up and down, counterbalancing means for normally holding the receptacle in raised position, adjusted to permit the receptacle to move downward under a load, and a valve for said opening, connected with said mechanism to open when the receptacle moves downward, said mechanism comprising a pair of levers having fixed axes, hangers resting on said levers, a link connecting said levers together, a rod connecting said link and valve together, and a connection from the end of one lever to said means.

4. A sand separator comprising a receptacle having a discharge opening, supporting mechanism whereby said receptacle is movable up and down, counterbalancing means for normally holding the receptacle in raised position, adjusted to permit the receptacle to move downward under a load, and a valve for said opening, connected with said mechanism to open when the receptacle moves downward, said mechanism and valve being connected together by a vertically disposed rod, said receptacle containing a guide for said rod, and said mechanism including a system of levers whereby said rod moves faster than the receptacle.

5. A sand separator comprising a receptacle having a discharge opening, supporting mechanism whereby said receptacle is movable up and down, counterbalancing means for normally holding the receptacle in raised position, adjusted to permit the receptacle to move downward under a load, and a valve for said opening, connected with said mechanism to open when the receptacle moves downward, said valve having a rod which extends upward through said receptacle, said mechanism having means to move said rod downward faster than the receptacle to open said valve.

6. A sand separator comprising a receptacle having a discharge opening, supporting mechanism whereby said receptacle is mov-

able up and down, counterbalancing means for normally holding the receptacle in raised position, adjusted to permit the receptacle to move downward under a load, and a valve 5 for said opening, connected with said mechanism to open when the receptacle moves downward, said valve having a rod which extends upward through said receptacle, said mechanism having means to move said 10 rod downward faster than the receptacle to open the valve, a housing for said rod, and means to support the upper end of said housing.

7. A sand separator comprising a receptacle having a discharge opening, supporting mechanism whereby said receptacle is movable up and down, counterbalancing means for normally holding the receptacle in raised position, adjusted to permit the receptacle to move downward under a load, and a valve for said opening, connected with said mechanism to open when the receptacle moves downward, said valve having a rod which extends upward through said receptacle, said mechanism having means to move said rod downward faster than the receptacle to open the valve, and said rod having means to limit its endwise motion and thereby determine the extent of movement of the 30 receptacle.

8. A sand separator comprising a receptacle having a discharge opening, supporting mechanism whereby said receptacle is movable up and down, counterbalancing

means for normally holding the receptacle 35 in raised position, adjusted to permit the receptacle to move downward under a load, and a downwardly opening valve for said opening, connected with said mechanism to open when the receptacle moves downward, 40 said mechanism including long and short levers above the receptacle, the top of said receptacle having hangers engaging said levers, said means including a pivoted arm with an adjustable weight thereon, and said 45 arm being connected to said long lever.

9. A sand separator comprising a receptacle, a valve for the lower end of said receptacle, a valve rod extending up through the receptacle, means connected to the upper end of said rod for automatically opening said valve, a baffle plate for preventing the sand from overflowing with the water, provided with an upwardly extending flange over which the water passes, but which 55 checks the sand, said plate being formed to permit the back wash from said flange to carry the sand downward into the receptacle, a housing for said rod, and means to attach the upper end of said housing centrally of said flange, said housing thereby held in position by said baffle plate.

Signed by me at Chicago, Illinois, this 11th day of March 1914.

RAYMOND W. DULL.
